UNITED STATES PATENT OFFICE.

JOHN C. CULLIGAN, OF RICHLVILLE, NEW YORK.

TRACE-HOLDER.

1,123,106.

Specification of Letters Patent. Patented Dec. 29, 1914.

Application filed March 7, 1913. Serial No. 752,714.

To all whom it may concern:

Be it known that I, JOHN C. CULLIGAN, a citizen of the United States, residing at Richville, in the county of St. Lawrence 5 and State of New York, have invented new and useful Improvements in Trace-Holders, of which the following is a specification.

This invention relates to trace holders; and it has for its object the provision of a 10 device of this character which will include a guard which may be mounted on the whiffletree and positioned immediately at one side of the trace end whereby to positively hold the same against accidental displacement 15 from the whiffletree.

Another object of the invention is the provision of a retaining device which is also adjustable on the whiffletree and adapted to be engaged directly against the surplus or 20 extremities of the trace ends and to hold the same directly confined against the whiffletree and which will be so designed that it will accommodate itself to the surplus end of the trace according to the length thereof.

25 With these and other objects in view, the invention consists of certain novel features of construction, combination and arrangement of parts, as will be hereinafter described and claimed.

30 In the accompanying drawings:—Figure 1 is a perspective view of a portion of a whiffletree, showing the application of the device thereto; Fig. 2 is a top plan view, showing the retainer adjusted to accommodate itself to the short terminal of the trace; and Fig. 3 is a section, taken on line 2—2 of Fig. 2.

The whiffletree 1 herein illustrated is provided near its trace receiving end with a 40 vertical passage 2. The trace guard 3 is preferably constructed from a single piece of metal, preferably wire, which is bent to provide superimposed arms 4, which are flared relatively in the direction of the outer 45 end of the whiffletree, the inner ends of the arms being offset from the plane of the flared portions and arranged in parallel relation and provided with terminal eyes 5. The parallel terminals of the arms 4 50 brace the opposite sides of the whiffletree and as illustrated the eyes 5 are alined with the passage 2, so as to receive therewith a pivot pin 6. The flared arms 4 are connected with each other by a vertical guard 55 bar 7, which is adapted to lie immediately

at one side of the trace and at a point forwardly of the whiffletree receiving eye 8, whereby to positively prevent the ends of the whiffletree from passing through the eye when the trace is in an applied position. 60

The point of juncture of the arms 4 with the guard bar 7 is coiled, as at 7', thereby rendering the arms 4 resilient for a purpose which will hereinafter be described. 65 It will be observed after the pin 6 is inserted through the eyes 5 and the alined opening 2 the same is thence bent upwardly, as at 8'. The bending of the pin is required to prevent any accidental displacement 70 thereof, in view of the resilient nature of the arms 4. Furthermore, the resiliency of the arms 4, frictionally binds the same to a certain extent with the upper longitudinal edges of the trace and prevents any accidental lateral movement of the trace guard 75 in one direction.

A retainer 9 is employed for holding the surplus end of the trace confined behind the whiffletree and directly thereagainst. Said 80 retainer is constructed from a single piece of metal, preferably wire bent to provide superimposed arms 10, which are connected with each other by a vertical bar 11. The arms 10 terminate in alined eyes 12, which 85 pivotally receive the pin 6, so as to permit the retainer to be adjusted angularly of the guard 3 and with relation to the trace receiving end of the whiffletree. The point of juncture of the vertical bar 11 with the arms 90 10 is coiled, as indicated at 11', the coiled portions performing a like function as that specified for the trace guard member 3.

From this construction, it is evident that the retainer may be adjusted to the position 95 shown in Fig. 1 to engage against the trace end when there is considerable surplus in the material, while as shown in Fig. 2, the retainer may be adjusted in the direction of the trace receiving end of the whiffletree and 100 confined against the trace when the end rearwardly of the eye 8 is of minimum length.

A trace holder constructed as described is extremely simple, may be manufactured at a relatively low cost and when applied to 105 the whiffletree as described will effectually serve to hold the trace end in an applied position, while serving further to facilitate the operation of connecting or disconnecting the trace, as is evident.

Having thus described my invention, what I claim is:—

A trace holder for whiffle trees comprising a guard member having superimposed arms adapted for the reception of a trace therebetween and connected with each other by a vertical bar disposed at one side of the whiffle tree, said arms having alined eyes, a pivot pin extending through said eyes and whiffle tree, a retainer member supported by the pin, said member comprising superimposed arms for the reception of the free end of the trace therebetween, said arms being connected with each other by a vertical bar disposed at the opposite side

of said whiffle tree, and the arms of said guard and retainer members at their point of juncture with said bars being formed to provide spaced pairs of vertically disposed coils operating to compress said arms into effective engagement with the opposite edges of the trace to prevent movement of the latter within the holder.

In testimony whereof I affix my signature in presence of two witnesses.

JOHN C. CULLIGAN.
